LOCKING DEVICE

Solomon Wise, Cleveland, Ohio

Application January 27, 1934, Serial No. 708,678
Renewed November 20, 1935

2 Claims. (Cl. 70—122)

This invention relates to a spare tire lock of the class wherein a bolthead or nut is received and enclosed in a multipart lock housing, the parts of which are intended to be locked against separation.

By virtue of its novel construction, this locking device is extremely simple to operate and install. It is also durable and of a rugged construction intended to resist the efforts of unauthorized persons in obtaining separation of the parts.

It may be said that one object of this invention is to provide a locking device for enclosing and preventing the removal of a nut which in turn secures the device in position, the said locking device possessing the characteristic of having a two-part housing that is held when in cooperation against separation in at least two zones. Another object of the invention is to provide a nut-lock that will allow the manipulation of the nut or bolt enclosed within the nut-lock housing by the fingers of the hand or some suitable tool.

It is the aim of this invention to provide a two-part lock housing, one of the parts being of such depth as to accommodate a nut or bolthead, the other of the parts acting as a closure in mounting the locking device manipulatable to obtain jointure of the two parts in non-separable relation. The relationship between the parts of the housing is such that they are secured together in opposed zones, namely at the top and bottom of the assembly, a releasable lock occupying the top zone so that upon opening of the lock the closure will tend to fall away from the other portion, and thus uncover the nut-head. This movement is assisted by the action of a spring. Accurate centering of the housing in mounting the same is a matter of little or no concern to the operator since the closure may be considered as self-centered.

Other objects and advantageous features of this invention will be observed from the following detailed description and accompanying drawing, wherein like characters of reference designate corresponding parts, and wherein—

Figure 1 is a side elevation of the preferred form of my locking device.

Figure 2 is a bottom view of the device shown in Figure 1.

Figure 3 is a front elevation of the device of Figure 1.

Figure 4 is a vertical longitudinal section through the device showing the locking arrangements and the manner in which the nut is received and enclosed within the locking housing.

Figure 5 is an elevation, partly in section, disclosing the manner in which the housing parts are separated.

Figure 6 is an elevation of the back side of the closure member of the housing.

Figure 7 is a fragmentary view of the upper interior zone of the mounting section of the housing illustrating the downturned edge behind which the locking bolt operates.

With reference to the drawing, I have shown my device as being made up essentially of three elements, namely, a two-part lock housing and a locking device for preventing separation of the parts of the housing. The housing may be conveniently divided, for purposes of description, into a mounting section A and a closure section B, the mounting section A being adapted to be mounted on a stud, such as that shown at C, to encompass and enclose the nut D, and the closure section B may be mounted thereon and locked thereto through the provision of locking instrumentalities, generally indicated at E, carried thereby. As regards the mounting section A, this member may be a simple stamping having a deformed portion 1 in the rear surface that is knurled as at 2 for cooperating with the walls of an aperture in the carrier bracket F, Figure 4, to prevent turning of the housing with respect thereto. The flange 3 of this stamping is provided with a rectangular aperture 4 in its bottom zone. The marginal edge of the flange is also downturned as at 5 to present a surface behind which the bolt of the lock may work. The mounting section A therefore practically comprises a housing or casing for the stud or head or a bolt to be locked against unauthorized access thereto by the use of my device.

Referring now to the closure member B, this part may be a die-casting of the configuration shown wherein an end portion is provided with an inwardly projecting hollow extension of larger and smaller diameters, the larger portion 6 being formed with an aperture or slot 8 for the locking bolt 7 and the inner portion 6a providing an inner barrel to receive the inner locking cylinders of the locking mechanism or parts. This locking mechanism is of a known type invented by me and is not material to this invention because any suitable locking mechanism may be used in lieu thereof. On the inner side of the closure member B is an inset flange 9, Figures 5 and 6, from which depends a locking tongue 10 to be received in the rectangular aperture 4 in the mounting section or casing A. The closure member B is of such construction that the flange

9 cooperates with the inside surface of the part A and the body of the closure will overlie the marginal edge of said part A so as to be substantially flush therewith. The larger portion of the hollow extension or inner barrel 6 of the member B accommodates the outer key barrel 11, which barrel carries the outer set of concentric cylinders or sleeves forming a part of the locking mechanism E. The key barrel 11 also carries 10 the locking bolt 7 as shown in Figures 4 and 5 most clearly.

The reduced portion 6a of the inner cylinder barrel 6 has mounted thereon and therearound a coil spring 12 which normally tends to push 15 outwardly on the closure member B. As shown in Figure 4 when the closure member B is placed on the mounting section or casing A the spring 12 is compressed against the wall of this latter member A and when the lock bolt 7 is released 20 the spring tends to separate the parts A and B as shown in Figure 5. The locking mechanism as stated may be of conventional design, being preferably of the multiple or concentric cylinder type, each of the cylinders being spring-urged 25 in one direction and being movable into lock releasing positions by means of the key K after a manner well known in this art. The key barrel 11 is equipped with a knurled manipulating surface 14 at its outer-most portion. The closure member B is bulged in the zone 15 to accommodate nuts, studs, or bolt heads of varied lengths or sizes in an obvious manner. The sizes of these nuts or heads or studs vary in reference to different types of automobiles and different types 30 of other appliances with which my lock may be used. To lock the closure member B on the casing or mounting section A, said member B is moved inwardly toward the part A from the position in which the member B is shown in Figure 5, 40 and the key barrel 11 is turned in a clockwise manner by manipulation of the knurled portion 14 of the key barrel 11 to move the lock bolt 7 in a rightward manner to engage it behind the locking flange or web 5. When the lock is closed 45 in the above manner the spring 12 is of course compressed and tends to push outward upon the closure section or member B. By manipulation of the key K which controls the proper pushing of the inner and outer concentric locking cylinders G of the locking mechanism, the key barrel 11 may be unlocked and turned to the position of Figure 5 or to the right as shown in Figure 6, whereby to withdraw the lock bolt 7 from its engagement with the flange or web 5 whereupon 50 the spring 12 will tend to push the closure section B to its open position of Figure 5. The tongue 10 will hold the parts in the position of Figure 5 until the closure section B is raised to disengage the tongue from the slot or aperture 55 4. The operator does not have to shake or pound

the lock to cause separation of the parts A and B in view of the use of the spring 12. Moreover, this spring is very desirable in performing the function of an anti-rattling spring as it maintains the parts A and B under pressure such that rattling 5 vibration of these parts is entirely prevented. It is to be understood that the lock unit of the present invention may be disposed upon the cooperating parts for which it is to be used for locking purposes, in different positions depending 10 upon the location of such parts and the limitations of the spaces where the lock units may be employed. It is immaterial whether the lock units are utilized in conjunction with stud bolts or nuts applied to bolts or the like, because it 15 is effective under all conditions of use with such members to prevent unauthorized access thereto.

Having thus described my invention, what I claim as new and desire to secure by Letters Patent of the United States, is:—

1. A tire lock of the class intended to be mounted upon a stud and to receive and enclose a nut on the shank of the stud, which comprises a mounting section having a webbed portion, said mounting section having an aperture therein, a closure member, a lock carried by said closure member having a part for cooperation with the web to prevent separation of the closure with respect to the mounting section when the said closure member is mounted thereon, a tongue formed as a part of the closure member for cooperation with the walls of the aperture in the mounting section to prevent separation of the closure and mounting section in such zone, and resilient means mounted on said lock intermediate said mounting section and closure for urging the separation of its closure and its mounting section when the former is mounted on the latter.

2. A lock of the class described comprising a mounting section forming an open faced casing, a closure section applied to the open face of the casing and comprising a tongue to interlockingly engage said casing at one portion thereof, said tongue constituting a hinge-like support for the closure section capable of sustaining the closure section in a partially open position relatively to the casing, a lock bolt engageable with and disengageable from the casing at an opposite portion thereof, said mounting section being provided with a portion to receive a nut or head of a stud bolt for preventing access thereto, when the closure section is in closed position on the mounting section, locking mechanism carried by the closure section cooperative with the lock bolt to control the latter and spring means operative 55 incident to disengagement of the lock bolt for urging said closure section into partially open position with said closure section sustained on the mounting section by the tongue aforesaid.

CERTIFICATE OF CORRECTION.

Patent No. 2,043,872,

June 9, 1936.

SOLOMON WISE.

It is hereby certified that error appears in the printed specification of the above numbered patent requiring correction as follows: Page 2, second column, line 37, claim 1, for "its" first occurrence, read the; and that the said Letters Patent should be read with this correction therein that the same may conform to the record of the case in the Patent Office.

Signed and sealed this 15th day of September, A. D. 1936.

(Seal)

Henry Van Arsdale
Acting Commissioner of Patents.
